METHOD FOR GENERATING STEAM

Donald N. Felgar and Nathan L. Dickinson, Alliance, Ohio, assignors to The Babcock & Wilcox Company, New York, N.Y., a corporation of New Jersey

Filed Oct. 21, 1955, Ser. No. 542,055

2 Claims. (Cl. 122—459)

The invention relates in general to a method and apparatus for generating vapor and, more particularly, is concerned with a method and apparatus for generating vapor while the vaporizable fluid is above the critical pressure.

A steam generator operating above the critical pressure of water (3206.2 p.s.i.a. and 705.4° F.) produces steam from liquid water under conditions quite unlike the generation of steam from the boiling phenomenon at pressures below the critical pressure. When steam is generated at a pressure above the critical, there is a continuous rise in temperature, and the conversion from water to steam occurs without the presence of vapor and liquid of different densities. Further, the fluid exhibits gas-like properties at the critical pressure and above the critical temperature. Because of these properties, the prior art super-critical vapor generators have been of the once-through type in which water is pumped up to pressure at or above the critical and flows through a heating zone in a confined flow path, and issues from the end of that path as steam above the critical temperature of 705.4° F.

Once-through type boilers operating at pressures below the critical pressure have involved difficulty during operation due to the deposition of the liquid dissolved solid impurities at a position where the final liquid is evaporated. In that case, however, there are two phases simultaneously existing and the liquid holds all the solids. Deposition occurs when all of the liquid is evaporated.

Few steam generating units have operated at pressures above the critical, and thus, there is little experience to indicate whether or not the deposition of solid impurities in the liquid occurs during transition from water to steam. It has generally been assumed, based on the kinetic theory of gases, that conversion to steam must take place at or about the critical temperature of 705.4° F. but because of the non-ideal nature of H_2O there has been no clear evidence as to whether or not deposition actually occurs during this conversion.

We have discovered that the deposition of the liquid carried solids does occur when supercritical pressure water is heated and, further, that the deposition occurs at temperatures at or above the critical temperature, 705.4° F. Moreover, we have discovered that in some circumstances a solid deposition occurs at fluid temperatures and pressures considerably above the critical. For instance, at 7500 p.s.i.a. deposition occurs at approximately 880° F. We have also discovered that the deposition occurs when the fluid passes through a specific volume equal to that existing at its critical point of 3206.2 p.s.i.a. and 705.4° F. and that this critical specific volume occurs at temperatures above the critical temperatures as a direct function of pressure.

This discovery when applied to a steam generating unit operating with water above its critical pressure is of considerable practicable importance because it promotes such design and operation of steam generating units that

2

they may successfully cope with the detrimental effects of deposition, such as high tube temperature and corrosion.

Accordingly, the present invention is directed to a method of generating steam above the critical pressure of 3206.2 p.s.i.a. in which the water is pumped up to a predetermined pressure and then directed in a confined stream through a heat transfer zone to receive heat from a source thereof. The heat absorption of the fluid is controlled so as to maintain the point at which the fluid reaches its critical volume at a predetermined position in said heat transfer zone, said critical volume being determined from a known pressure-temperature-specific volume relationship of the steam, and the critical specific volume being defined as a specific volume of the fluid at its operating pressure equal to the specific volume of water at its critical point (3206.2 p.s.i.a. and 705.4° F.).

The various features of novelty which characterize the invention are pointed out with particularity in the claims annexed to and forming a part of this specification, but for a better understanding of the invention, its operating advantages and specific objects attained by its use, reference should be had to the accompanying drawings and descriptive matter in which there is illustrated and described a preferred embodiment of the invention.

25 In the drawings:

Fig. 1 is a curve showing the pressure-volume-temperature relationship for water above the critical pressure;

Fig. 2 is a curve showing pressure-temperature curve of the critical constant volume line;

30 Fig. 3 is a schematic diagram illustrating the operation of the invention;

Fig. 4 is an alternative apparatus for carrying out the invention.

35 Fig. 1 graphically presents the relationships of the specific volume of water above the critical pressure under various conditions of pressure and temperature. It is intended that the term, water, is used to define the molecule H_2O and the definition is not limited to the liquid phase only. The specific volume increases with temperature increases under constant pressure heating conditions. Also indicated in Fig. 1 is the critical point on the critical pressure line which defines the pressure, temperature and specific volume at the point. These values (3206.2 p.s.i.a., 705.4° F., 0.0503 cu. ft./lb.) are well established by a number of experimenters and may be found in any of the usual reference materials. Drawn through the critical point of this curve there is the dotted line denoting a constant critical volume line.

40 Fig. 2 is a cross plot of Fig. 1 in which pressure and temperature are the co-ordinates and the constant critical specific volume line is drawn thereon. Further indicated is the line CDE which represents the progressive states of the fluid passing through a supercritical pressure steam generator and shows the temperature rise and the pressure drop. At the intersection of the line CDE with the critical specific volume curve, we have discovered that depositions occur in the steam generator. Thus, it can be seen that deposition occurs not at the critical temperature exclusively but at various temperatures above the critical. For instance, at 7500 p.s.i.a. deposition occurs at 880° F. and is considerably above the critical temperature of 705.4° F. If a steam generator were arranged and operated on the assumption that the transition or deposition occurs at 705.4° F. and at a particular position in the steam generator, the unit would be found to be operating incorrectly. The deposition would actually occur some 174° F. removed from this estimated position and might be at a position where the resultant corrosion and/or high tube temperature would make the unit unsafe.

45 In Fig. 3 the invention is indicated as applied to a once-through steam generator in which the feed pump 10

pumps water to a pressure greater than 3206 p.s.i.a. and causes it to flow through conduit 12. The pressure in the conduit 12 is maintained by an outlet valve 14 and the conduit is divided into two heating zones, a liquid heating zone 15, and a steam heating zone 16. Temperature and pressure measuring devices 19, 20 are placed at position 18 intermediate of the two heating sections and adjacent the outlet valve 14. Thus, as a fluid flows through the conduit 12 and is heated from a source (not shown) the temperature and pressure distribution of the unit is indicated by the pressure and temperature instruments 19 and 20. With the relationships indicated in Figs. 1 and 2, the temperature at which the critical volume occurs may be selected from the constant critical specific volume line for the pressure at the position 18. This temperature will indicate the position where deposition occurs. By regulating the pump flow rate and the heat input rate into the flowing fluid, the deposition or precipitated solids may be laid down in the conduit 12 in the position 18 and this position is arranged in the unit so as to extend the life of the conduit while making the heating process more efficient. The control of heat input into the water may be attained by any appropriate means, such as tilting burners, gas recirculation, heated fluid recirculation and control of the heated fluid flow rate through the conduit to produce a proper heat content per pound of fluid flowing at the point of precipitation. These means control heat absorption of the flowing fluid in two basic ways; control of heat input to the tubes containing the fluid, and control of the fluid flow rate to vary the heat absorbed per pound of fluid flowing. Gas recirculation and tilting burners are ways of controlling heat inputs while water circulation and flow rate control are ways of controlling the heat absorbed per pound. All of these ways, however, can be used to control the heat content of the water at any particular position in the steam generating unit.

Knowing that, irrespective of the fluid pressure, deposition always occurs when the fluid reaches a specific volume equal to the specific volume at the critical point, the vapor generation process can be arranged to occur at any given position in a heat exchange zone. This is done by measuring and controlling the pressure and temperature of the fluid so that the corresponding critical volume for that pressure occurs at a predetermined position to thus have the deposition occur there. This is a method of generating vapor which may be applied to water under any pressure conditions above the critical so as to most effectively generate vapor.

In Fig. 4 there is indicated an alternative method of generating vapor in which the fluid is pumped through a conduit 21 by a feed pump 22. The conduit has a preheating portion 24 and superheating portion 26. These two portions are separated by a connecting line 28 having a valve 30 therein and arranged with a by-pass line 32 having a valve 34 therein. At the outlet end of the superheating section 26 there is an outlet control valve 36. Pairs of pressure and temperature measuring devices 38, 39, and 40 are located in the bypass line 32, in the connecting line 28 and just upstream from the outlet valve 36, respectively. In this arrangement the water is pumped to a pressure above the critical by the pump 22 and is heated from a source (not shown) as it passes through the preheating section 24. Normally, the water flows through the open valve 30 in the connecting line 28 and is superheated in the superheating section 26. Thence it passes to a point of use through the outlet control valve 36. In the event that the feed liquid becomes contaminated by condenser leakage, for example, the connecting valve 30 is closed and the bypass valve 34 is opened to allow the preheated fluid to pass through the bypass conduit 32. The heat input to the pressurized fluid is regulated so that the critical constant volume occurs at approximately the position of the control valve 34. The regulation of the fluid heat input is based on the

temperature and pressure measurements before the control valve. The valve 34 is arranged to provide an essentially adiabatic throttling process in the fluid passing through the valve. Thus, pressure drop is controlled to be sufficient to cause the high pressure fluid to pass through its critical volume during the adiabatic throttling process. The outlet valve 36 maintains the steam pressure above the critical. The control could be by hand or any well-known automatic means.

The throttling process is indicated in Fig. 2 where the line CDE represents the normal pressure and temperature distribution of the fluid passing through a supercritical pressure steam generator. The line DFE' represents the fluid conditions as it passes through the unit. The throttling process is represented by the line DF, thus with the critical volume occurring during a pressure expansion, the solids are deposited in the connecting line 32. The connecting line is arranged to be unheated so that the deposition would not interfere with the operation of the vapor generating unit.

This new method provides for the operation of a supercritical pressure steam generator for a considerable period of time without having to be shut down due to detrimental effects on the tubes from solid deposition.

The sources of thermal energy have not been shown or described because the invention may be carried out with any of the well-known types such as, hot liquid or hot combustion products.

Further, the process is considered a method for separating liquid carried solids from water above its critical pressure. Under such circumstances, methods of mechanical separation are inadequate because the fluid never contains two phases, i.e. steam and water, each of a different density.

While in accordance with the provisions of the statutes, we have illustrated and described herein a specific form of the invention now known to us, those skilled in the art will understand that changes may be made in the form of the apparatus disclosed without departing from the spirit of the invention covered by our claims, and that certain features of the invention may sometimes be used to advantage without a corresponding use of the other features.

We claim:

1. The method of generating steam in a forced circulation once-through vapor generator in the range of pressures above the critical pressure of 3206.2 p.s.i.a. comprising supplying solids-bearing water at a pressure greater than said critical pressure and at a temperature less than the critical temperature of 705.4° F., conducting the pressurized water in heat transfer relationship with a thermal energy source so as to increase its temperature above 705.4° F., and controlling the position with respect to the thermal energy source at which the fluid reaches its critical specific volume within said range of pressures and thereby precipitates the liquid-borne solids by regulating the heat absorbed by the fluid, said critical specific volume for said range of pressures being the specific volume corresponding to the specific volume which would exist were the water at its critical point, 3206.2 p.s.i.a. and 705.4° F., the temperature at which said critical specific volume occurs being above 705.4 and in the uppermost portion of said range of pressures being at least 100 degrees F. above the temperature of 705.4° F.

2. The method of generating steam in a forced circulation once-through vapor generator in the range of pressures above the critical pressure of 3206.2 p.s.i.a. comprising supplying solids-bearing water at a pressure greater than said critical pressure and at a temperature less than the critical temperature of 705.4° F., conducting the pressurized water in heat transfer relationship with a thermal energy source so as to increase its temperature above 705.4° F. to a point where the heated fluid is in a state which is just before it reaches its critical specific volume, said critical specific volume for

said range of pressures being a specific volume corresponding to the specific volume which would exist were the water at its critical point, 3206.2 p.s.i.a. and 705.4° F., the temperature at which said critical specific volume occurs being above 705.4° F. in the uppermost portion of said range of pressures being at least 100 degrees F. above the temperature of 705.4° F., and adiabatically expanding the heated fluid through a pressure range above the critical pressure to cause said fluid to pass through its critical specific volume at a predetermined position out of contact with said thermal energy source to precipitate said water borne solids.
